UNITED STATES PATENT OFFICE.

MAURICE LOUIS LETROTEUR, OF PARIS, FRANCE.

MOTOR-PLOW.

1,266,502.

Specification of Letters Patent. Patented May 14, 1918.

Application filed December 1, 1917. Serial No. 204,876.

To all whom it may concern:

Be it known that I, MAURICE LOUIS LETROTEUR, manufacturer, a citizen of the Republic of France, of 7 Rue Montaigne, Paris, France, have invented new and useful Improvements in Motor-Plows, of which the following is a specification.

The present invention relates to motor plows; and it proposes, briefly, an implement of the character specified embodying certain improvements hereinafter fully described, in consequence whereof the disadvantages ordinarily involved in the types of motor plows in general use are completely overcome.

According to the invention, the plow is constructed in such a way as to require a single driver only, in place of the two usually needed, and to enable the tilting to be carried up to within a few yards of the verge of the field, at the same time avoiding the necessity of the plow being turned at the end of the field and the loss of time resulting therefrom; the plow being always held in working position, so the blades are caused to enter the ground in the proper manner. The invention resides in and has for its object the provision of these and other improved features, considered both structurally and from the standpoint of relative arrangement.

The accompanying drawings show diagrammatically by way of a purely demonstrative but by no means restrictive example a motor plow according to the present invention, neither the constructional details of the tractor proper, nor of the motor and guiding mechanism being shown, as they may be of any suitable type and do not present any novel features.

Figure 1 of the said drawings is a side elevation of the machine.

Fig. 2 is an end view thereof partly in vertical section looking from the back, that is to say looking from left to right of Fig. 1.

Fig. 3 is a plan of Fig. 2.

a indicates a main frame provided at one end with two driving wheels *b* and *b'*, and at the other end with a guiding wheel *b*². This frame carries the motor and the power transmitting and steering members which are not shown. A double steering arrangement is provided, also two seats located opposite to each other, the forward or backward movement being obtained in any suitable manner.

Suspended beneath the frame *a* is a swinging frame *c* to which there are fixed frames *d* carrying the shares and one of the side members of which is provided with a vertical extending rigid arm *c'*. The frame *c* is mounted upon a shaft *e* carried in two supporting arms *f*, *f'* which are mounted upon a divided shaft constituted by two short axles *g*, *g'* carried in a line with each other in plumber blocks *h*, *h'*, depending from the main frame *a* to which they are fixed.

Fixed upon the axle *g* is a lever *i* which can be moved over a notched quadrant *j* and held in any one of the three positions I, II, III, Fig. 1, by means of a usual hand controlled spring pawl.

The lever *i* is connected, by means of a link *k* which extends parallel to the arm *f* to which it is equal in length, to the arm *c'* of the frame *c*. The operation of the lever *i* in one direction or the other will consequently cause an oscillation, in the corresponding direction, of the swinging frame *c* in suchwise that the frames *d* carrying the plow blades will take up the positions I—I', 2—2', 3—3' corresponding respectively to the positions I, II, and III of the lever in question.

In a bracket *l*, fixed upon the main frame *a* there is supported and guided a screw *m*, provided with a hand wheel *m'* and working in a nut *c*², Fig. 2, which is pivotally mounted at *c*³ in a fork *c*⁴ rigidly fixed to the swinging frame *c*. By manipulating the hand wheel *m'* the driver of the machine can, therefore, lower or raise at will the said frame and the plow blades so as to enable the plow to turn the earth over to the depth required. Due to the parallel arrangement and equality in lengths of the link *k* and the arm *f*, it will be apparent that the arm *c'* of the swinging frame *c* always remains parallel to the hand lever *i* whatever position said lever may occupy. The consequent result is that the height or position of the shaft *e* in relation to the main frame *a* and to the fixed axle *g*, or in other words the "earthing" or "unearthing" of the plow, has no influence at all upon the inclination of the plow blades.

The operation of the improved machine is as follows:—

For purposes of transport the plow is horizontal, the lever *i* being in the vertical position I while the swinging frame *c* with

the frames *d* and the plow blades occupy the position shown in full lines at *l*, *l'* in Fig. 1.

For tilling when traveling forward, that is to say with the guiding wheel *b*² to the fore, the driver first of all earths the plow to the necessary depth by suitably manipulating the hand wheel *m'* so as, by means of the screw *m*, to adjust the shaft *e* of the swinging frame *c* to the height desired. He then pulls the lever *i* toward the position II until the plow blades penetrate into the earth. During the travel of the machine the lever *i* will then automatically take up the position II and will lock the swinging frame and the plow blades in the position 2—2' corresponding thereto, thus consolidating the plow and the tractor and preventing any lack of striking or taking the earth on the part of the plow.

For tilling when traveling backward the lever *i* is manipulated in the reverse direction, toward position III, so as to cause the swinging frame *c* and the plow blades to take up the position 3—3'.

It will be observed that the movement for again raising the blades of the plow, that is to say the swinging of the frame *c*, is very easily effected by means of the lever *i* in view of the fact that the two parts of the plow are balanced so that, consequently, only the inertia of the members and the friction of the earth upon the plow blades have to be overcome. If, however, this manipulation should be found too laborious screw gearing may be substituted for the lever in question.

It will be clear that, by removing the frames *c* and *d*, the apparatus will be transformed into an ordinary tractor suitable for all purposes.

Finally it will be readily understood that the invention is not strictly limited to the exact arrangement hereinbefore described and shown, by way of example, in the accompanying drawings but that, without departing from the invention, modifications may be made in the constructional details of the apparatus and of its various members, or certain members may be replaced by equivalent mechanical devices.

Having now particularly described and ascertained the nature of my said invention and in what manner the same is to be performed I declare that what I claim is:—

1. A motor plow comprising a main frame for carrying the motor mounted on wheels and adapted to travel either forward or backward, a frame located beneath and articulated to the main frame to swing vertically in either direction, a double swing plow carried by said frame to swing therewith, and a manipulating lever connected to said frame articulated to effect its swinging movements whereby the driver can cause the

plow to take up the positions required for tilling both when traveling forward or backward.

2. A motor plow comprising a main frame for carrying the motor mounted on two main wheels and one guiding wheel and adapted to travel either forward or backward, a double swing plow suspended from said frame by means of an articulated swinging frame, and a manipulating lever connected to said frame whereby the driver can cause the plow to take up the positions required for tilling both when traveling forward or backward.

3. A motor plow comprising a main frame for carrying the motor mounted on wheels and adapted to travel either forward or backward, a double swing plow suspended from said frame by means of an articulated swinging frame, means for vertically adjusting the axis of articulation of said swinging frame relatively to said main frame, and a manipulating lever connected to said frame whereby the driver can cause the plow to take up the positions required for tilling both when traveling forward or backward.

4. A motor plow comprising a main frame for carrying the motor mounted on wheels and adapted to travel either forward or backward, a double swing plow suspended from said frame by means of an articulated swinging frame, a screw mounted to rotate but not move endwise in a bearing fixed to said main frame, a pivoted nut working on said screw and carried by said swinging frame, a hand wheel on said screw for rotating it in order to vertically adjust the axis of articulation of said swinging frame relatively to said main frame, and a manipulating lever connected to said frame whereby the driver can cause the plow to take up the positions required for tilling both when traveling forward or backward.

5. A motor plow comprising a main frame for carrying the motor and mounted on wheels, brackets depending from said main frame, a rock shaft mounted in said brackets, arms on said rock shaft, an axle carried by said arms, a swinging frame supported on said axle, plow blades fixed on said frame, a hand lever on said rock shaft, an arm on said frame, a link connecting said arm to said lever, said link corresponding in length and extending parallel to said arms of said rock shaft, and means for holding said lever in any position to which it is moved in order to adjust the said plow blade carrying frame.

6. A motor plow comprising a main frame for carrying the motor and mounted on wheels, brackets depending from said main frame, a rock shaft mounted in said brackets, arms on said rock shaft, an axle carried by said arms, a swinging frame supported on said axle, bars detachably mounted in said frame, earth tilling tools fixed to said bars, a

hand lever on said rock shaft, an arm on said frame, a link connecting said arm to said lever, said link corresponding in length and extending parallel to said arms of said rock shaft, and means for holding said lever in any position to which it is moved in order to adjust said plow blade carrying frame.

7. A motor plow comprising a main frame for carrying the motor and mounted on wheels, brackets depending from said main frame, a rock shaft mounted in said brackets, arms on said rock shafts, an axle carried by said arms, a swinging frame supported on said axle, a screw mounted to rotate but not move endwise in a bearing fixed to said main

frame, a pivoted nut working on said screw and carried by said swinging frame, a hand wheel on said screw for rotating it in order to vertically adjust the axis of articulation 20 of said swinging frame relatively to said main frame, a hand lever on said rock shaft, an arm on said frame, a link connecting said arm to said lever, said link corresponding in length and extending parallel to said arms of 25 said rock shaft, and means for holding said lever in any position to which it is moved in order to adjust said plow blade carrying frame.

MAURICE LOUIS LETROTEUR.
